Atlys

UNITED STATES PATENT OFFICE.

ANDREW G. ANDERSON, OF WOLLASTON, MASSACHUSETTS, ASSIGNOR TO CARR FASTENER COMPANY, OF CAMBRIDGE, MASSACHUSETTS, A CORPORATION OF MAINE.

FASTENER.

Application filed April 24, 1924. Serial No. 708,724.

This invention aims to provide an improved socket for a separable fastener.

In the drawings which illustrate a preferred embodiment of my invention,

5 Fig. 1 is an elevation view showing the socket attached to a support;

Fig. 2 is a section on the line 2—2 of Fig. 1, being partly in elevation;

10 Fig. 3 is a side view partly in section and partly in elevation of the parts of the socket prior to assembly thereof;

15 Fig. 4 is a section, partly in elevation, of the socket showing the relation of the parts prior to crimping the prongs over the head of the attaching screw;

Fig. 5 is a side elevation of the preferred form of socket; and

Fig. 6 is a rear elevation of the preferred form of socket.

20 Referring to the preferred form of my invention, I have shown a flush-type socket including a casing preferably formed from a single sheet of metal. The casing illustrated includes a body part 1 generally cylindrical in cross section, a flange 2 at the outer end of the casing, a front face 3 preferably dished towards a stud-receiving aperture 4 which is surrounded by a rounded stud-engaging wall 5 formed by turning inwardly the edges of the front face adjacent the stud-receiving aperture 4. The front face also presents two generally radial tool-receiving slots 6—6 extending outwardly from the periphery of the stud-receiving aperture. The socket illustrated presents at its inner end a screw 7 having a square head 8 which is secured rigidly to the casing by a plurality of prongs 9 extending from the innermost end of the casing. These prongs 40 overlie the edges of the head 8 of the screw 7 and are clenched against the adjacent face of the head, while the opposite face of the head, adjacent the corners, lies against the flat surfaces 10 located between the prongs 9.

45 Within the socket I have provided a sealing disk 11 normally urged into aperture closing position by a spring 12 seated against the inner face of the head 8 of the screw. The sealing disk normally covers the stud-receiving aperture 4 and the tool-receiving slots 6—6, thereby to exclude dust and dirt from the casing when a stud is not secured thereto, and to contribute to the operation of certain types of studs not described herein.

Assuming the parts of the socket to be unassembled, as illustrated in Fig. 8, assembly thereof is in the following order,—first the sealing disk 11 is dropped into the casing, the spring 12 is then dropped into the casing upon the sealing disk, and the head 8 of the attaching screw is then placed, with the corners thereof, between the upstanding generally curved prongs 9, by first inserting one corner thereof between two of the prongs and then tipping the other three corners into engagement with the flat surfaces 10 between the other prongs. As illustrated in Figs. 3 and 4, the prongs 9 are normally slightly curved so that the head of the screw cannot pass by them without tipping the screw relative to the casing. Thus the parts are temporarily held in the relation shown in Fig. 4 until a die (not shown) upsets the prongs against the face of the head 8 of the screw and seats the head of the screw on the flat surface 10, as hereinbefore stated. When the socket is assembled, as illustrated in Figs. 5 and 6, there can be no rotation of the casing without corresponding rotation of the attaching screw.

The body 13 of an automobile or like support is first prepared for attachment of the socket thereto by drilling a socket-receiving recess therein and a relatively small hole concentric therewith into which the screw 85 may be inserted. To attach the socket to the body of the car, I first manually place the socket in the socket-receiving recess and the screw-receiving hole and then with the use of a screw-driver or other suitable tool 90 blade inserted in the tool-receiving slots 6, 6, I rotate the socket in a clockwise direction. Thus the screw turns into the body 13 and draws the closely fitting body part 1 of the casing into the socket-receiving recess 95 until the flange 2 seats against the outside surface of the automobile body 13.

The socket herein described and illustrated is simple and inexpensive but presents a neat appearance when secured to an 100 automobile, the only part thereof which extends beyond the outer surface being the flange 2, which, being of greater diameter than the body of the socket, covers the edges of the socket-receiving recess which would otherwise appear unsightly.

While I have shown and described a preferred embodiment of my invention, it will

be understood that I have done so for purposes of clarification and not for purposes of limitation, my invention being best defined in the following claims.

Claims—

1. A fastener element including a casing having a cylindrical inner end portion presenting a plurality of edge seats and a plurality of attaching prongs and an attaching member having one end thereof seated against said edge seats and held in fixed relation with said casing by said prongs.
2. A fastener element including a one-piece casing and an attaching screw, said casing presenting at its inner end a plurality of alternating edge seats and projecting portions and said screw presenting a head portion seated against said edge seats and held thereagainst by said projections to prevent relative rotation between the casing and the screw.
3. A fastener element presenting at one end thereof a plurality of prongs, a plurality of edge seats between said prongs, and an attaching member having a head seated against said seats and secured to said fastener element by said prongs.
4. A separable fastener element including a casing presenting a tubular wall, an attaching post having a head entered from the inner end of said casing and presenting portions abutting against the inner edge of said tubular wall, and lugs projecting from the inner end of said tubular wall and bent beneath said head to hold said attaching post in assembled relation to said casing.
5. A separable fastener element including a casing presenting a tubular wall, an attaching post having a head entered from the inner end of said casing and presenting portions abutting against the inner edge of said tubular wall, and lugs projecting from the inner end of said tubular wall and abutting against the sides of said head to oppose relative turning movement between said casing and said attaching post.
6. A socket for a separable fastener including a one-piece casing, the inner end of which presents a plurality of flat spots and prongs located on the periphery thereof, an attaching screw presenting a head for engagement with said flat spots, said head held in fixed relation to said casing by bending said prongs over the periphery and against the face of said head thereby to permit rotation of said casing and said screw as a unit.
7. A socket for a separable fastener including a casing presenting a plurality of alternating seats and prongs at one end thereof and an attaching member presenting a head seated against said seats and held in a predetermined relation to said casing by said prongs.
8. A socket for a separable fastener including a casing presenting a plurality of alternating seats and prongs at one end thereof and an attaching member presenting a head having a plurality of straight sides, the corner portions of said head seated against said seats, said prongs bent over the straight edges and against the adjacent face of said head to hold said head against said seats and for preventing relative movement of said casing relative to said attaching member.
9. A socket for a separable fastener including a one-piece casing, the inner end of which presents a plurality of flat spots and prongs located on the periphery thereof, an attaching screw presenting a head for engagement with said flat spots, said head held in fixed relation to said casing by bending said prongs over the periphery and against the face of said head thereby to permit rotation of said casing and said screw as a unit.
10. A flush type socket comprising in combination a casing and a screw for attaching said casing to a carrying part, said casing formed of a single piece of metal presenting integrally a front face having a stud receiving aperture therein, a flange about said front face to conceal the edge of the hole in which said socket is to be mounted, a tubular body part of smaller diameter than said flange, said screw having a head entered in said body part from that end thereof opposite said front face, and means permitting turning of said screw by turning of said casing, said means including tool receiving recesses in said front face and screw head receiving recesses in said body part.
11. A flush type socket including a casing having a stud receiving aperture and presenting its major diameter at the outer end thereof, a securing element entered from the rear end of said casing and rigidly secured thereto and tool receiving means formed in the front face of said casing for reception of a tool thereby to rotate said casing and securing element as a unit when securing said casing to a support.
12. A socket for a separable fastener including a casing having an attaching member rigidly secured to one end thereof and a plurality of tool-receiving slots located in the other end of said casing for reception of a tool to turn said casing and attaching member as a unit thereby to secure the same to a support.

In testimony whereof, I have signed my name to this specification.

ANDREW G. ANDERSON.
